KNITTING MACHINE

Howard Severn Regar, Cleveland Heights, Ohio,
assignor to The Wovenright Knitting Co.,
Cleveland, Ohio, a corporation of Ohio

Application January 14, 1935, Serial No. 1,649

7 Claims. (Cl. 66—133)

This invention relates broadly to knitting machines and more specifically to an improved thread carrier for guiding a reinforcing thread into the knitting needles within a localized area 5 of the fabric. The invention further pertains to the arrangement of the fibers in the knitted fabric and contemplates the resultant advantages of such structure in the fabric.

The improved thread guide and thread carrier 10 embodying the present invention is adapted for use in conjunction with a knitting machine of the circular, reciprocating type such as the machine disclosed in the United States patent to Lawson, No. 1,458,833, dated June 12, 1933, the 15 actuating mechanism therefor being constructed for use with the control members of such machine.

One of the objects of the present invention is to construct a thread carrier which is so ful- 20 crumed within the machine as to effect its retraction from the knitting needles during the oscillatory movement thereof.

Another object of the invention is to provide a 25 thread carrier which will position the thread for entry within the knitting needles during one stage of the reciprocative movement of the needle cylinder in the knitting cycle of the machine, position the thread above the path of the needle during the reverse movement of the needle cylinder 30 and maintains the thread from engagement within the knitting needles during subsequent knitting operations of the machine.

Another object of the invention is to construct 35 a thread carrier having a throat or guiding face thereon which will automatically feed the knitting needles during a portion of the reciprocative cycle of the needle cylinder and then cause the thread to be elevated above the needles in non-engaging position during the remaining portion 40 of reciprocative movement of the cylinder.

Another object of the invention is to construct 45 a reinforcing area in the stocking or similar article wherein the reinforcing thread will be knitted and floated in alternate courses, thus providing a fabric having a corrugated outer surface which affords greater strength and wearing qualities and possesses greater yieldability and less harshness of texture than fabrics in which 50 the reinforcing threads are plated in consecutive courses in the knitting.

Referring to the drawings wherein the present embodiment of the invention is illustrated:

Figure 1 is a fragmentary view, partially in 55 section, of a circular knitting machine illustrat-

ing the arrangement of the improved thread carrier in such machine;

Figure 2 is a plan view of the machine illus- 5 trated in Figure 1, showing the position of the improved thread carrier in relation to its appurtenances, certain portions of the machine being illustrated somewhat diagrammatically herein;

Figure 3 is a detailed diagrammatic perspective view, drawn upon an enlarged scale, of the thread carrier and a fragmentary portion of the 10 knitting needles;

Figure 4 is a detailed view in perspective of the thread carrier embodied in the present invention;

Figure 5 is a transverse sectional view through 15 the forward portion of the thread guide shown in Figure 4;

Figure 6 is a detailed view showing a front elevation of the thread carrier and the relation 20 thereof to the throat plate when the carrier is disposed in its operative position;

Figure 7 is an elevational view of a stocking 25 illustrating an example of the reinforced area produced by use of the improved thread carrier and thread guide embodied in the present invention;

Figure 8 is a diagrammatic transverse sectional view through the reinforced portion of the stocking shown in Figure 7 and illustrating the disposition of the floated or unknitted thread in 30 alternate courses of the fabric as formed during the knitting operation.

Figure 9 is an elevational view somewhat dia- 35 grammatic illustrating the position of the needles and threads carried therein when the needle cylinder is reciprocated counter clockwise.

Figure 10 is a similar view illustrating the 40 relation of parts and the threads when the needle cylinder is revolved in the opposite direction to that shown in Figure 9.

The knitting machine illustrated in Figure 1 45 embodies generally a base 10 having mounted thereon a frame 11, which supports a pattern cylinder 12, a knitting needle cylinder 13 and the needle picker 14 therefor. This plate is provided with tapered cam blocks 40 forming tracks or grooves 41 into which the butt or lug of the needles are extended to effect their vertical reciproca- 50 tion within the operating cycle. The cams are disposed to effectuate the elevation of the knitting needles as the needle cylinder therefor rotates or oscillates past the yarn carrier fingers. As the needles are elevated the threads are caught in the hooked portions thereof where they are retained until the cam effecting their 55

retraction is engaged, at which time the latch of the needle is forced open, the thread passed thereover, a second thread gathered, the first thread then being cast off the shank of the needle 5 closing the latch and the second thread drawn into interlooped engagement with the contiguous loops. Since all of these mechanisms and the operation thereof are of the usual well known form and constitute per se no part of the 10 present invention a further or more detailed description thereof is deemed unnecessary herein. Above the knitting needle cylinder there is a latch ring 15 upon which there is mounted a throat plate 16 and a plurality of thread carriers 17. 15 The thread carrier 17—*a*, *b*, *c* and *d* as illustrated in Figure 2 constitute the thread feeding medium for the yarns forming the body of a stocking or similar fabric product. These members comprise respectively an arm having an aperture 20 extended vertically through the end portion thereof for receiving and guiding the thread into the knitting needles when the arms are lowered into operative position.

The thread carrier 18 embodying the present 25 invention is adapted for coordinated operation with the arms 17 and is suitably adapted to guide an additional thread or reinforcing fiber within a localized plated area in the knitted fabric. In detail the thread carrier 18 comprises an arm 30 apertured adjacent its outer end to retain a thread and drilled in the opposed end to receive a pin mounted in a post 19, supported by a stanchion 20. The thread carrier 18 is oscillated about its pivotal support by a rocker arm 35 21 coordinated with linkage 22 controlled by a series of cams 23 mounted upon the pattern drum 12. The rocker arm 21 is arranged to elevate the thread carrier 18 through the influence of the cam 23 and linkage therefor, the thread carrier being moved to feeding position by a tension spring 24 supported by the pintle 25 mounted upon the post 19 and a stud 26 secured in the end portion of the arm above and rearward the fulcrum thereof.

40 The forward portion of the thread carrier or arm 18 is formed with a transverse slot 27 inclined downwardly from the center of the outer side of the arm to a point adjacent the base of its opposed face. The slot as will be seen in Figure 5 defines a triangular block or cam which guides the thread during the operation of the machine. In the upper portion of the arm above and centrally disposed in relation to the slot 27 there is an aperture 28 which is provided to receive the thread from the thread tension mechanism, not shown, under working conditions. When the arm is lowered to operative position the thread is guided through the aperture 28 to the slot 27 and thence over the lower edge thereof 45 to the thread guide 16 where during a portion of the knitting operation it is fed into the knitting needles. Upon the reverse reciprocative movement of the needle cylinder the thread is drawn through the slot 27 to a point adjacent the crest thereof and above the contiguous needles in the cylinder so that knitting engagement of the thread with such needles will be rejected throughout this portion of the operative cycle of the machine.

50 As will be seen in Figure 6 the mouth piece or throat plate 16 is formed with inclined face 29, the elevated portion thereof merging with a shoulder 30 formed with a recess 31 therein which guides the threads from the arms 17 and 55 18 into the needles during the knitting opera-

tion. The opposed end of the guiding surface 29 is similarly formed with a shoulder portion 32 having a recess 33 for guiding the thread from the carriers 17—*a*, *b*, *c*, and *d*. The upper portion of the shoulder 32 is relieved to prevent the 5 thread discharged through the slot 27 in the thread carrier 18 from being engaged within the recess 33 and to prevent the entry of the thread from said carrier within the knitting needles during reverse reciprocative operation of the 10 needle cylinder when the thread is withheld from entry to the knitting needles.

15 Since the present invention pertains to the introduction of the thread within a localized area of the fabric it will be understood that the operation of the machine as referred to hereinafter will be confined to the reciprocating cycle of the knitting needle cylinder. It will also be understood that the thread carriers 17—*a*, *b*, *c* and *d* perform their operative functions in the usual 20 and heretofore well known manner.

In operation, while the cylinder is reciprocating in the direction indicated by the arrow in Figure 3 the needles are elevated as they pass the thread guide 16 to a position where the threads guided 25 through the fingers 17 will be engaged thereby. (See Figure 10.) Continued movement of the cylinder will cause the needles to be lowered under influence of the cam blocks thus causing the thread to close the latch of the needle, lock the 30 thread so gathered and eject the looped thread formerly engaged by the hook riding on the shank of the needle at this period of the operating cycle. As the needle cylinder 13 is reciprocated in the opposite direction, the thread "a" 35 is guided through the aperture 28 into the slot 27 where it is directed through the throat 27a thereof over the surface 29 and into the needles 35. During the reverse reciprocative movement of the knitting needle cylinder 13 the thread will 40 be drawn through the open end of the inclined slot where it is lifted and guided to a higher plane adjacent the throat 27b of said slot. The point of discharge of the thread during this operating cycle is sufficiently elevated above the knitting needles to prevent the entry of the thread 45 *a* into the hooked ends of the needles. Thus the thread in the complete operative cycle will be carried by the arm 18, introduced into the needles and knitted in the fabric during the reciprocative movement of the cylinder in one direction but will be elevated and held from engagement in the needles upon the opposite reciprocative movement of the needle cylinder, the thread *a* being carried or floated over the surface of the 50 fabric as illustrated in Figure 8 until the cylinder resumes its former reciprocative movement where the thread will be again introduced into the needles and knitted and plated on the outer surface in the knitted fabric structure. 55

60 As illustrated in Figure 9 wherein the thread "a" is shown as a dotted line in the interest of clarity the inclined slot 27 will permit the thread "a" to rest upon the surface 29 of the thread guide 16 when the cylinder is moving in the direction indicated by the arrow, while the thread is so positioned the engagement with the elevated needles is effected. When the needle cylinder is reciprocated in the opposite direction as 65 illustrated in Figure 10 the thread "a" will be guided over the surface 29 of the guide 16 until the needle within which it is lodged passes a point adjacent the inner edge of the arm 18. Continued movement of the cylinder will cause the thread to be guided upwardly through the 70 75

inclined slot 27, the angle thereof being suitably disposed to cause the thread to clear the shoulder 34 and to be guided upon the surface 32. As clearly illustrated in Figure 10 when the thread 5 is elevated through the inclined slot 27 and is resting upon the surface 32 the knitting needles 35 have attained their descending position in the operating cycle and will be thus withheld from knitting engagement throughout this portion of 10 the operating cycle, the thread "a" being merely floated over the surface of the fabric until it is forced downwardly through the inclined slot 27 upon the reverse reciprocative cycle where it will reach the position shown in Figure 9 and will be 15 seized by a needle for engagement in the knitting needles.

As the cylinder revolves counter clockwise (Fig. 9) all of the threads or yarns including the thread "a", guided by the thread carrier 18, 20 are knitted throughout this cycle of revolution of the needle cylinder. As the cylinder revolves in a clockwise direction the heel and toe yarns carried by the thread carriers 17—*a*, *b*, *c* and *d* are knitted into the fabric as shown in Fig. 10. In 25 this cycle, however, at the beginning of travel of the cylinder the reinforcing thread "a" rides upwardly in the slot 27 of the thread guide 18 over the relieved or beveled corner of the shoulder 32, onto the ledge formed by the shoulder 32 where 30 it is maintained above the hooks of the needles 35 in non-engageable or non-knitting position. While so positioned the thread "a" is engaged in the last needle 35—*a* as shown at the end of the reinforced portion of the fabric which was knitted 35 while the cylinder revolved in a counter clockwise direction (Fig. 9). Since the thread "a" is held taut by the usual take-up mechanism, not shown, the thread "a" will be held above the remaining needles (Fig. 10) until the clockwise 40 revolution of the needle cylinder is completed, and at this particular point is resting taut against the last needle which has been pushed up out of action by the needle raising pick 14 on the previous revolution as is customary in machines 45 of this type. With the first counter clockwise movement (Fig. 9) of the cylinder, the needle raising pick 14 (Fig. 1) engages and lifts the last needle 35—*b* so that the thread "a" will be caught between the needle above referred to and 50 the needle now lifted by needle raising pick 14, whereupon continued movement of the cylinder it is carried back and positioned upon the surface 29 of the throat plate until caught by the succeeding needles and inter-knitted in the fabric 55 throughout the counter clockwise revolution of the cylinder. When the cylinder renews its clockwise rotation the thread "a" is again carried above the needles in non-engaging position and the cycle heretofore described is repeated.

At the end of the first clockwise movement, heretofore described, the yarn "a" is held taut between the finger 18 and the last needle in which yarn "a" has been knit, and is also resting on surface 32. It will be understood that the 60 cylinder continues to rotate a few degrees after the last needle of the needles in action takes its last stitch. During this continued movement the yarn "a", due to its position on the surface 32, above the level of the needles in action, rides 65 over the heads of the lowered needles in action until the cylinder comes to the end of its rotation. At this point, yarn "a" has floated across the cylinder above the fabric and is resting against the last needle which was raised by picker 70 75 14 on the last previous counter-clockwise move-

ment of the cylinder, being held taut by the take up. As the cylinder now rotates in the counter-clockwise position, just before this last needle above referred to passes the surface 32 the pick 14 elevates the needle next to the needle above 5 referred to, thereby locking the floated yarn "a" between these two needles. This upward movement of the needle does not raise nor change the position of yarn "a" with reference to the needles as the finger 18 is so close to the needles as to 10 keep the yarn down to the level of the mouth-piece and yarn "a" is not resting against the needle being raised. As the locked yarn "a" passes the surface 32, under the influence of slot 27, the yarn "a" drops off surface 32; is 15 carried over to the opposite side of the mouth-piece and is knit in the regular way. Moreover, the needles in action are raised before they pass surface 32, as shown in Fig. 9, thereby causing the hooks of these needles to be above the surface of yarn "a" and be caught by the knitting needles the same as the other heel and toe yarns in the regular way, being held in position for knitting by the recess 31. After being knit into the fabric during the counterclockwise rotation, 20 the cylinder now rotates in a clockwise position and the yarn "a" is again lifted upon the surface 32 by the method heretofore described, at the time of the succeeding clockwise rotation, then 25 the operation above described is repeated. 30

Although the process of making the upper or last half of the toe of a stocking is done by widening, the pick 14 still continues to raise one needle during each succeeding counterclockwise rotation. When making the upper or last half of the 35 toe, a second set of picks (not shown) provided in machines of this type, go into action on the opposite side of the machine, and each of these picks lowers two needles, while the pick 14 still continues to raise one during each rotation, 40 thereby making a gain of one needle being lowered during each rotation of the cylinder resulting in a widening operation which brings the short butt needles back to the same position or the same number of needles in action as when 45 the construction of the toe was started.

It will be recognized in the above operation that the thread "a" is inter-knitted in the fabric throughout the translation of the cylinder in one direction, but since it was rejected from the opposite reciprocal movement of the cylinder will form a fabric in which the thread lies only in alternate courses thereby providing a fabric having the wear resisting virtues of other forms of knitted reinforcement, and in addition possessing the advantage inherent in the ribbed or corrugated surface, including greater yieldability, elasticity, less harshness and less rigidity than in other fabrics wherein the reinforcing fibers are introduced in consecutive courses and consequently so matted or packed as to effectuate a rigid texture. 50 55

In the production of hosiery and similar articles made in accordance with the teachings of this invention the floated threads "a" are sheared 60 adjacent the point at which they are engaged within the knitted fabric at the points 42 and 43 in Figure 8, having short projecting ends along each of the marginal edges of the reinforced area. 65

The arrangement of the cams 23 and the linkage coordinated therewith effectuates the elevation of the arm 18 after the reinforcing area is 70 knitted, this operation being comparable with that of the guide fingers 17—*a*, *b*, *c*, and *d*. It will be noted, however, that the fulcrum point 36 75

of the arm 18 is disposed rearwardly and below the fulcrum of the arms 17 and that through this arrangement the end portion of the arm is retracted or drawn arcuately from the needles 5 during the oscillatory movement of the arm.

Although the foregoing description is necessarily of a detailed character, in order that the invention may be completely set forth, it is to be understood that the specific terminology is not intended to be restrictive or confining, and that various arrangements of parts and modifications of structural detail may be resorted to without departing from the scope or spirit of the invention as herein claimed.

15 I claim:

1. In a knitting machine having a periodic rotative reciprocating knitting needle cylinder, a thread carrier for guiding a thread into and out of engagement with said needles, said thread carrier comprising an arm having an aperture therein for receiving a thread, a cam in the end portion of said arm, said cam being formed to guide the thread into said needles during the rotation of said needle cylinder in one direction 20 and to elevate the thread above the needles in non-engaging position during the reverse rotation of the needle cylinder.

2. In a knitting machine, a thread carrier comprising an arm, means therein for supporting a thread, a cam in the end portion of said arm formed to elevate the thread to non-knitting position during a portion of the operating cycle of the machine.

3. In a knitting machine having a periodic rotative reciprocating knitting needle cylinder, a thread carrier for guiding a thread into and out of engagement with said needles, said thread carrier comprising an arm having an aperture therein for receiving a thread, the end portion of said 40 arm having a transverse slot therein inclined from one side of the arm to the opposed side thereof, said aperture communicating with said slot, the inclination of said slot being adapted to guide a thread extended over the surface thereof 45 into the knitting needles during the rotative movement of the needle cylinder in one direction and to elevate the thread in non-engaging position with the needles during the opposite rotative movement of the needle cylinder.

50 4. In a knitting machine having a periodic rotative reciprocating knitting needle cylinder, a thread carrier for guiding a thread into and out of engagement with said needles, said thread

carrier comprising a vertically actuatable arm having an aperture in the end portion thereof for receiving a thread, a cam contiguous said aperture constituting a guiding surface for the thread, said cam embodying an inclined body 5 the lower surface thereof being disposed to guide the thread into the knitting needles when the needle cylinder is rotated in one direction, the higher surface of said cam being disposed to prevent entry of the thread guided thereon when 10 the needle cylinder is rotated in the opposite direction.

5. In a knitting machine having a periodic reciprocative reciprocating knitting needle cylinder, a thread carrier for guiding a thread into 15 and out of engagement with said needles, said thread carrier comprising an arm having an aperture therein for receiving a thread, a cam in the end portion of said arm, said cam being formed to guide the thread into said needles during the 20 rotation of said needle cylinder in one direction and to elevate the thread above the needles in non-engaging position during the reverse rotation of the needle cylinder whereby the thread carried by said arm will be knitted in alternate 25 courses of a fabric during the operative cycle of the machine.

6. In a knitting machine, a thread carrier comprising an arm, means therein for supporting a 30 thread, a cam in the end portion of said arm, said cam being formed to guide a thread into the knitting needles in a portion of the knitting cycle and to deflect the thread from knitting engagement with the needles during another portion 35 of the knitting cycle.

7. In a knitting machine, a thread carrier, a throat plate, a shoulder therein coordinated with said thread carrier for guiding a thread into knitting engagement with the knitting needles throughout a portion of the operating cycle of 40 the machine, a second shoulder in said throat plate, disposed above the first named shoulder and coordinated with said thread carrier for guiding said thread into non-knitting engagement with the knitting needles throughout another portion 45 of the operating cycle of the machine, and means in said thread carrier for elevating the thread over the first named shoulder and upon the second named shoulder whereby said thread is alternately guided into and out of knitting engagement with the knitting needles during a 50 complete operating cycle of the machine.

HOWARD SEVERN REGAR.
